Primary Examiner — Keli L Hill(74) *Attorney, Agent, or Firm* — AdamsIP, LLC; J. Hunter Adams; Stephen Thompson(57) **CLAIM**

What is claimed is the ornamental design for a bottle insulator with a resealable cap, as shown.

DESCRIPTION

FIG. 1 is a front elevation view of a bottle insulator with resealable cap, embodying my new design, the rear view being identical thereto;

FIG. 2 is a side elevation view thereof;

FIG. 3 is a top plan view thereof;

FIG. 4 is a bottom plan view thereof;

FIG. 5 is a perspective view thereof; and,

FIG. 6 is another side view thereof, shown in use.

The broken lines in the drawings that represent the portions of a bottle are for the purpose of illustrating environment that forms no part of the claimed design.
